Primary Examiner — Prabhakar G Deshmukh(74) *Attorney, Agent, or Firm* — Thomas J. Oppold;
Larkin Hoffman Daly & Lindgren, Ltd.(57) **CLAIM**

The ornamental design for a bean bag toss game target, as shown and described.

DESCRIPTION

FIG. 1 is a top perspective view of a bean bag toss game target showing my new design.

FIG. 2 is a bottom perspective view thereof.

FIG. 3 is a top plan view thereof.

FIG. 4 is a bottom plan view thereof.

FIG. 5 is a rear elevation view thereof.

FIG. 6 is a front elevation view thereof.

FIG. 7 is a right side elevation view thereof; and,

FIG. 8 is a left side elevation view thereof.

The broken lines indicate unclaimed portions and form no part of the claimed design. The broken line showing bags indicate environment and form no part of the claimed design.
